UNITED STATES PATENT OFFICE

WILLIAM J. DE WITT, OF AUBURN, NEW YORK, ASSIGNOR TO SHOE FORM CO., INC., OF AUBURN, NEW YORK, A CORPORATION OF NEW YORK

EXPANSIBLE TOE FORM

Application filed January 26, 1931. Serial No. 511,165.

This invention relates to an improvement in an expansible toe form of the general type shown in my Patent No. 1,736,780, dated November 26, 1929 which comprises a hollow thin walled shell of resilient flexible material and cross means connecting the walls of the shell.

Such forms have been found to be objectionable for various reasons among which are the following: First, the toe of the form being closed and substantially rigid contacts with any roughness or unevenness in the shoe in which it is inserted and prevents its advance into the proper position, second, there is a backward tendency exerted against the toe form when in the proper position which is resisted only by the rearward part of the form and to overcome which prongs which engage the inner sole have been provided, as shown in my Patent No. 1,632,955, dated June 21, 1927, or back part wires have been attached to the toe form to contact with the heel counter, as shown in my Patent No. 1,646,016, dated October 18, 1927, third, the expansion of the form can obviously take place only at the rearward part and hence only the material at the ball of the shoe is placed under tension.

The primary object of this invention is to provide a toe form having a shell with an open ended toe and cross braces by which the side walls of the shell are yieldably expanded throughout their length and thus bear with a balanced pressure against those portions of the shoe with which they contact.

A toe form embodying this invention overcomes the various objections noted above, since its open end permits the advance of the form to the proper position in the shoe and also allows the forward ends of the side walls, as well as the rearward ends, to shift laterally, thus providing a balanced pressure throughout the extent of the side walls so that not only are all portions of the toe properly tensioned but also the tendency of the form to move backward is resisted by the contact of the whole surface of the form with the shoe and not by the contact of the rearward portion only.

One embodiment of a toe form made ac-

cording to this invention is described in the following specification and illustrated in the accompanying drawing in which:

Figs. 1 and 2 are a plan view and side elevation respectively of such a toe form in its normal condition; and

Figs. 3 and 4 are bottom plan views thereof, the forward end of the form in Fig. 3 being contracted, and the rearward end proportionately expanded, while the rearward end of the form in Fig. 4 is contracted and the forward end proportionately expanded the cross braces remaining in the same position in both figures.

In the drawing the toe form comprises a shell 10 and cross braces 20. The shell is of resilient, flexible material, for example celluloid, having side walls 11 and 12 which terminate in inwardly projecting flanges 13 and 14 respectively. The toe 15 of the form is open ended and the flanges 13 and 14 are not connected as in the toe forms shown in the patents above cited. In the flanges 14 and 13 near the rear end thereof are formed arcuate slots 16 and 17 respectively with which the cross braces co-act.

The cross braces 20 comprise two bars 21, 22, the forward end of each bar being pivotally secured to the flanges 13 and 14 by rivets 23. The rearward end of each bar is slideable in a slot in the flange opposite to the flange to which the bar is pivoted and in the present instance carries a rivet 25, the shank of which passes through the slot. Suitable bosses 26 are formed in the flanges by which the bars are engaged to hold them removably in the desired adjusted position.

When the toe form is inserted into the shoe the open end of the shell permits it to advance the proper amount, regardless of any roughness or unevenness at the toe. In Figs. 3 and 4 are illustrated the positions the form would assume when inserted into shoes differing in contour. After the form has been inserted the cross bars 21, 22 are swung forwardly in the slots 16 and 17 to expand the shell. This movement of the bars tends primarily to expand the rearward part of the shell but it is obvious that if, for example, the rearward end of the side wall

11 is in contact with the wall of the shoe while the forward end of the side wall 12 is away that end will be advanced into contact by the pressure of the cross bar 22. At the same time if the forward end of the side wall 11 is away from the shoe wall that end of the side wall 11 will move outwardly, and while the rearward end of the side wall would tend to be moved proportionately inwardly by this action of the side wall, it would, on the other hand, be held in the proper position by the cross bar 22. Consequently after the form has been advanced into the proper position and adjusted by the cross bars, the side walls will bear with balanced pressure throughout their extent upon the portions of the shoe with which they are in contact. The material forming the toe of the shoe will thus be properly plumped out and at the same time this contact of the shell with the shoe toe will resist the tendency of the toe form to retreat and hold it in place until the cross bars have been retracted and the pressure of the shell against the toe of the shoe reduced.

The forward edge of the shell at the open toe 15 may, if desired, be stiffened slightly as by rolling or by the provision of a bead or narrow flange 30 for the purpose of giving this edge a trifle more stiffness or rigidity, and to render the sliding of the form into the forepart of the shoe without interfering appreciably with the expansion or contraction of the shell as described hereinabove.

55. While one embodiment of this invention has been shown and described I am not limited thereto since other embodiments can be made without departing from the spirit and scope of the invention as set forth in the following claims.

I claim:

1. An expandible toe form for insertion into the toe of a shoe comprising a hollow thin walled shell of resilient, flexible material having an open-ended toe and cross braces connecting the side walls of said shell, the side walls of the shell bearing throughout their extent with balanced pressure against those portions of the shoe with which they contact.

55. An expandible toe form for insertion into the toe of a shoe comprising a hollow thin walled shell of resilient, flexible material having an open-ended toe and cross braces connecting the side walls of said shell, one at least of said cross braces being adjustable to separate the side wall of the shell, and said side walls by reason of the open-ended toe, bearing with balanced pressure throughout their extent against those portions of the shoe with which they contact.

65. An expandible toe form for insertion into the toe of a shoe comprising a hollow thin walled shell of resilient, flexible material having an open-ended toe and inwardly

extending flanges, and cross braces engaging said flanges and connecting said shell walls and causing said walls to bear with balanced pressure throughout their extent against those portions of the shoe with which they contact.

4. An expandible toe form for insertion into the toe of a shoe comprising a hollow thin walled shell of resilient, flexible material having an open-ended toe and inwardly extending flanges, each flange having an arcuate slot and cross braces engaging said flanges, each cross brace being pivotally connected at one end to one of said flanges and slidably at the other end in the slot of the opposite flanges.

Signed by me at Auburn, New York this 21st day of January, 1931.

WILLIAM J. DE WITT.
